UNITED STATES PATENT OFFICE

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,398**, dated September 9, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

The principal subdivisions of the groundwork in this carpet are produced by a rectangular figure, A, which has, at diagonally-opposite corners, two smaller rectangular extensions, *a* and *b*. From the end of figure A, near the extension *b*, project two oblique borders, *d* and *e*, which serve to partly inclose an octagonal figure, B. The figure A is repeated on both sides of the figure B, as indicated in the photograph. D and E are two smaller octagons, placed at the end of the border *e*.

Within the figure A is a vase, F, holding a flower, G.

The groundwork of the figures A and B is checkered, as shown, and embellished with floral decorations.

I claim—

1. The design for a carpet, consisting of the figure A, having oblique extensions *a b*, substantially as shown.

2. The design for a carpet, consisting of the figure A *a b* and borders *d e*, substantially as shown.

3. The design for a carpet, consisting of the figures A, B, *d e*, D, and E, substantially as shown.

4. The design for a carpet, consisting of the figure A, having extensions *a b*, vase F, and flower G, substantially as shown.

The above specification of my invention signed by me this 30th day of July, 1879.

HENRY HORAN.
